UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

AIR CONDITIONING APPARATUS

Application filed May 28, 1926. Serial No. 112,374.

My invention relates to air conditioning apparatus and particularly to apparatus for both heating and moistening the air.

The invention has among its other objects 5 the production of a device of the kind described which is compact, convenient, durable, efficient and satisfactory for use wherever found applicable.

One form of the invention is embodied in 10 a heating unit adapted to be adjustably suspended from a steam pipe or hot water pipe and provided with means for advancing a column of air, the apparatus being so designed that a portion of the steam or hot 15 water is delivered to the air when the apparatus is in operation.

Many other objects and advantages of the 20 construction herein shown and described will be obvious to those skilled in the art from the disclosure herein given.

To this end my invention consists in the 25 novel construction, arrangement and combination of parts herein shown and described, and more particularly pointed out in the claims.

In the drawings, wherein like reference characters indicate like or corresponding parts;

Figure 1 is a rear elevation of an air conditioning device embodying the invention;

Figure 2 is a section taken on line 2—2 of Figure 1;

Figure 3 is a section taken on line 3—3 of Figure 2; and

Figure 4 is a central section taken through 35 an air conditioning device embodying another form of the invention.

Referring for the present to Figures 1 to 3 inclusive, the reference character 10 designates generally an air conditioning device embodying the invention and preferably comprising a housing 11 which in this instance is formed from upper and lower manifold members 12 and 13, respectively, and side plates 14. Secured to the manifold members 12 and 13 is a radiator core 16 preferably comprising upper and lower tanks 17 and 18, respectively. The radiator core 16 is preferably secured to the manifold members 12 and 13 by bolts 19 or the equivalent which extend

through the tanks 17 and 18. Formed in the manifold members 12 and 13 are passages 22 and 23, respectively, which communicate with the tanks 17 and 18, respectively. The tanks 17 and 18 communicate with each other 55 through tubes 25 which are preferably formed from relatively thin sheet metal, the tubes 25 being preferably provided with fins 26.

Screw-threaded into the manifold 12 is a 60 nipple 27 which communicates with the passage 22, and arranged coaxially with the nipple 27 and projecting into the manifold 13 is a nipple 28. The nipple 27 is preferably connected to a steam or hot water pipe (not 65 shown) by means comprising a pipe union 30 and the nipple 28 is preferably connected to a drain or return pipe (not shown) by means comprising a pipe union 32. This construction is more fully described in my copending 70 application Serial Number 28,369, filed May 6, 1925, but it is obvious that the housing 11 may be angularly adjusted about the coincident axes of the nipples 27 and 28.

Mounted upon the manifold 13 is a bracket 75 35 which supports an electric motor 36 adapted to drive a fan 37, the motor being connected with any suitable source (not shown) of electrical energy. Obviously, when steam or hot water is circulated through the radiator core 16 and the fan 37 is driven by the motor 36, a column of heated air will be advanced from the device.

Screw-threaded into the manifold 12 and communicating with the passage 22 is a 80 85 valved fitting 39 provided with a lever 40 whereby the valve may be opened or closed. Extending from the valved fitting 39 is a T fitting 42 provided with a plurality of perforations 44. This construction permits steam or hot water to flow from the passage 22 through the perforations 44 when the valve is in its open position. The valve is preferably controlled by means comprising a link 45 which connects the free end of the lever 40 with one end of a lever 46, the lever 46 being pivotally mounted intermediate its ends upon a bracket 47 mounted upon the housing of the motor 36. It will be noted that the other end of the lever 46 is provided with 90 95 100

a bearing member 48 engageable with one end of the motor shaft. A spring 49 secured to the lever 46 and to the bracket 47 urges the lever 46 in a clockwise direction (see Figure 2) and tends to keep the aforementioned valve in its closed position so that steam or hot water may not pass through the apertures 44. It will be readily understood by those skilled in the art that sufficient play is generally provided in electric motors so that the shafts may shift longitudinally therein. Thus in this instance the motor shaft is urged to the left (Figure 2) by the spring 49 but when the fan is in operation the resistance of the air causes the fan and shaft to assume the positions wherein they are shown in full lines in Figure 2. That movement is against the action of the spring 49.

20 The operation of the above described apparatus is substantially as follows: Assuming that the motor 37 is not in operation, the fan 37 and the motor shaft will be retained in the positions wherein they are shown in full lines in Figure 2 so that the valved fitting 39 does not permit the fluid to pass from the passage 22 through the apertures 44. If the motor 36 is then set in operation, the fan and motor shaft move into the positions wherein they are shown in dotted lines in Figure 2 and the valved fitting is opened. The fan then advances a column of air through the radiator core 16, the air being heated by steam or hot water flowing through the core. Simultaneously, moisture is supplied to the air by way of the passage 22, the valved fitting 39 and the apertures 44 in the T fitting 42.

40 Referring now to Figure 4 wherein I have shown another form of the invention, the reference character 60 designates generally an air conditioning device which preferably comprises upper and lower manifolds 61 and 62, respectively, and a radiator core 63. The manifolds 61 and 62 and the radiator core 63 are preferably identical with the aforementioned manifolds 12 and 13 and the radiator core 16, respectively. A bracket 65 mounted upon the manifold 62 is adapted to support an electric motor 66 having a shaft 67 carrying a fan 68a, the fan being adapted to advance a column of air through the radiator core 63. The device 60 may be supported from a steam or hot water pipe in substantially the same manner as the aforementioned device 10, the steam or hot water being circulated through the radiator core 63 by way of passages 68 formed in the manifolds 61 and 62. Screw-threaded into the manifold 61 and communicating with the passage 68 therein is a valved fitting 70, the valve of which is operated by a reciprocating valve stem 72. A compression spring 74 wound around the valve stem 72 normally holds the valve in a position wherein fluid may pass

through the fitting and engageable with the valve stem 72 is a lever 76 which is pivoted intermediate its ends upon a bracket 78 carried by the radiator core 63. One end of the lever 76 is engageable with the motor shaft 67 which is normally urged to the left (Figure 4) by a leaf spring 79 fixed to the bracket 65. The construction is such that when the fan 68a is not in motion, the shaft 67 holds the lever 76 in a position where it depresses the valve stem 72 against the action of the spring 74 and the passage through the valve fitting 70 is closed. However, when the motor 66 is set in operation the fan 68a and the shaft 67 move into the positions wherein they are shown in dotted lines in Figure 4 and the spring 74 functions to open the valve in the fitting. Fluid may then pass from the passage 68 in the manifold 60 through the fitting 70.

85 Screw-threaded into the fitting 70 is a T fitting 75 provided with perforations 76a which distribute any fluid which may pass through the fitting 70. The T fitting 75 is preferably identical with the aforementioned T fitting 42.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

200 What I claim as new and desire to secure by Letters Patent is:

1. In a device as described, a radiator provided with passages for a heating fluid, means including a valve connected to one of said passages for delivering a part of said fluid to the atmosphere, a fan including fan blades and a motor for advancing a column of air through said radiator, a shaft for said motor, said fan blades connected to said motor shaft, means for operating said valve, said valve operating means engaging said motor shaft, said motor shaft being capable of longitudinal movement, means urging said shaft in the direction of the advancing column of air to close said valve, said shaft being moved in the opposite direction and opening said valve when the fan is in motion.

110 2. In a device of the class described and in combination with a casing, a radiator core having passages for conducting an aqueous heating fluid, a pair of aligned conduits for conducting such fluid to and from said radiator core, said conduits serving as pivots upon which said casing may be rotated, means for delivering a portion of said heating fluid into the atmosphere adjacent said core, a fan mounted within said casing for projecting a current of moistened air through said core, and valve means associated with said de-

livering means and controllable by said fan.

3. In a device of the class described and in combination with a casing, a radiator core having passages for conducting an aqueous heating fluid, a pair of aligned conduits for conducting such fluid to and from said radiator core, said conduits serving as pivots upon which said casing may be rotated, means for delivering a portion of said heating fluid into the atmosphere adjacent said core, a fan mounted within said casing for projecting a current of moistened air through said core, valve means for controlling the delivery of fluid from said delivery means, and a lever operable by the axial movement of the shaft of said fan for controlling said valve.

4. In a device of the class described and in combination with a casing, a radiator core having passages for conducting an aqueous heating fluid, a pair of aligned conduits for conducting such fluid to and from said radiator core, said conduits serving as pivots upon which said casing may be rotated, means for delivering a portion of said heating fluid into the atmosphere adjacent said core, a fan mounted within said casing for projecting a current of moistened air through said core, valve means for controlling the delivery of fluid from said delivery means, resilient means for normally retaining said valve in closed position, and a lever operable by the axial movement of the shaft of said fan when in operation for opening said valve.

5. In a device of the class described and in combination with a casing, a radiator core having passages for an aqueous heating fluid, a pair of aligned conduits for conducting such fluid to and from said radiator core, said conduits serving as pivots upon which said casing may be rotated, tubular means having spaced apertures therein disposed in the upper portion of said casing for delivering a portion of said heating fluid into the atmosphere adjacent said core, a fan mounted within said casing for projecting a current of moistened air through said core, and valve means associated with said delivering means and controllable by said fan.

6. In a device of the class described and in combination with a casing, a radiator core having passages for an aqueous heating fluid, a pair of aligned conduits for conducting such fluid to and from said radiator core, said conduits serving as pivots upon which said casing may be rotated, tubular means having spaced apertures therein disposed in the upper portion of said casing for delivering a portion of said heating fluid into the atmosphere adjacent said core, a fan mounted within said casing for projecting a current of moistened air through said core, valve means for controlling the delivery of fluid from said delivery means, and a lever operable by

the axial movement of the shaft of said fan for controlling said valve.

7. In a device of the class described and in combination with a casing, a radiator core having passages for an aqueous heating fluid, a pair of aligned conduits for conducting such fluid to and from said radiator core, said conduits serving as pivots upon which said casing may be rotated, tubular means having spaced apertures therein disposed in the upper portion of said casing for delivering a portion of said heating fluid into the atmosphere adjacent said core, a fan mounted within said casing for projecting a current of moistened air through said core, valve means for controlling the delivery of fluid from said delivery means, resilient means for normally retaining said valve in closed position, and a lever operable by the axial movement of the shaft of said fan when in operation for opening said valve.

8. In a heating and moistening apparatus, a radiator core, means carrying said core and connected with the core for circulating a heating medium through said core, means for advancing a column of air through said core, and means communicating with said first mentioned means for delivering moisture to the column of air, said means including means extending along an edge of said core and providing means for spraying and delivering said moisture to said column of air.

9. In a heating and moistening apparatus, a radiator core, means for circulating a heating medium through said core, means for advancing a column of air through said core and means located between the core and air advancing means for delivering moisture to the column of air to thereby moisten the air prior to its introduction to the core, and means associated with the air advancing means for controlling the delivery of moisture from said last mentioned means.

In testimony whereof, I have hereunto signed my name.

ARTHUR B. MODINE.
